UNITED STATES PATENT OFFICE.

EDWIN R. MERRILL, OF COLUMBUS, OHIO, ASSIGNOR TO JOSEPH A. JEFFREY, OF COLUMBUS, OHIO.

MINING-MACHINE.

No. 878,976.

Specification of Letters Patent.

Patented Feb. 11, 1908.

Application filed January 15, 1901. Serial No. 43,319.

To all whom it may concern:

Be it known that I, EDWIN R. MERRILL, a citizen of the United States, residing at Columbus, in the county of Franklin and State of Ohio, have invented certain new and useful Improvements in Mining-Machines, of which the following is a specification, reference being had therein to the accompanying drawing.

10 This invention relates to improvements in mining machines of the class known as "long wall" machines, that is to say, machines each having a main frame or bed which can be propelled bodily along the face of the coal 15 and which carries the laterally projecting cutting apparatus.

The improvement consists in so constructing and arranging the parts that high speeded, reciprocating engines can be employed to 20 advantage; so that the cutting apparatus can be easily and quickly adjusted to vary the plane of its cutting relative to horizontal planes; so that the cutter wheel can be reversed without requiring any movement bodily of the whole machine, as is frequently 25 necessary when the cutters become stopped by the severe work put upon them or from other causes; so that the devices can be simplified and economically actuated to effect the advance of the machine; and in order to attain other ends, as will appear from the description below.

Figure 1 is a plan view of a mining machine embodying my improvements. Fig. 2 is a 35 side elevation of the same from the side of the cutting apparatus. Fig. 3 is a side elevation of the opposite side. Fig. 4 is a section on the line x, x of Fig. 1. Fig. 5 is a section on the line y, y of Fig. 1. Fig. 6 is a side view of 40 the combined valve chest and cylinder coupling, detached. Figs. 7 to 12 show details of the reversing mechanism. Figs. 13 and 14 are detached details of the cam adjustment 45 of the feed mechanism. Fig. 15 is a plan view of the bed frame. Fig. 16 is a cross section on the line z, z , of Fig. 1. Figs. 17, 18 and 19 are detached details of the cutting wheel hanger bracket. Fig. 20 is a detached detail of the central portion of the cutting 50 wheel illustrating its construction. Fig. 21 is a cross section on the line w, w of Fig. 20. Fig. 22 is a cross section on the line v, v of Fig. 20.

The machine shown comprises a main 55 frame or bed, a pair of reciprocating engines

for compressed air or similar agent, a laterally projecting cutter wheel, a wheel carrier or holder mounted on a pivotal axis, power shafting between the engines and the cutter wheel, supporting and guiding wheels for the bed, a bed advancing or moving apparatus having a rope winding shaft and drum, and an actuating mechanism driven by the engines for operating the said carriage moving shaft, together with other parts and details to be described.

The bed frame as a whole is indicated by A, the several longitudinal and transverse parts thereof being preferably cast integral and comprising the side parts a, a' , the end 70 cross parts a^1, a^2 and intermediate cross parts at a^4, a^5, a^6 , which serve as girders or braces and also as supports for the operative parts. The side bars a' at the rear end of the machine are inclined or curved inward as 75 shown at a^7 to permit the cutter wheel to be brought toward the central longitudinal line of the bed, or, in other words, to permit the bed frame to be brought close up to the face of the coal, thereby not only narrowing the 80 machine as a whole, but so disposing its several parts that the powerful side strains and torsional reactions which are particularly incident to machines of this sort are largely 85 eliminated and the power shafting and gearing are arranged compactly and close to the cutter wheel. The bed frame is also cast with the tubular bearings B, and with the expanded base plate C arranged vertically. C' indicates the cutter wheel as a whole. It 90 is constructed in a novel and peculiar manner, being cast in two halves c, c' which are bolted together at c^2 , this permitting it to be made accurately and providing against the flaws frequently incident to large castings; 95 and moreover it can readily be put in place or removed from the machine without separating the other parts. It is supported by means of two plates D, D', one above and one below the wheel. The plate D is at d bolted 100 to the part indicated as a whole by E, and the plate D' is secured to the lower end of the pivot element extending outward from the axis far enough to give vertical support to the wheel. The part indicated by E comprises a tubular 105 journal e, the vertically extended plate e', the bottom plate e² and a housing wall or flange e³. The journal e fits in the aforesaid box or bearing at B and the plate e' is fitted close to the plate C. The journal e provides a long axial 110

support for the part E and the cutter wheel carried thereby, this part E and those at D and D' constituting what I refer to as the cutter wheel support or carrier. At e^4 there are bolts engaging with the inner stationary plate E and situated in slots e^4 in the wheel carrier. These devices permit the firm fastening of the wheel carrier in place after it has been adjusted in the way to be more fully described, and also permit it to be released so that the adjusting devices can perform their work.

The cutter wheel C' is formed with a circular series of beveled teeth with which meshes a driving pinion F. The latter is on the cutter-wheel driving shaft G which is mounted at one end in the sleeve journal e in the bracket box B and at the other end in a bearing standard B' fastened to the bed frame near its outer edge.

H is the driving gear wheel on the shaft G.

I, I indicate the two reciprocating engines. They are mounted in relatively low horizontal planes and are provided with a common valve chest I'.

i, i are the guides for the cross heads connected to the piston rod, and from these cross-heads the pitman i^2 extends backward to the crank disks j on the transversely mounted crank shaft J.

The eccentrics K are placed close to the center of the machine and between them is the driving pinion L which meshes with the aforesaid wheel II on the cutter-driving wheel shaft. The eccentrics are connected with their valves in a peculiar manner, there being at M, M slides mounted in guide-ways which are connected to the valve rods m , m and pivotally connected to the eccentric rods m' , m' . The eccentrics can be released from the shaft to which they are connected through the medium of disks K'. These disks are each provided with a concentric slot k , formed entirely through the disks, and with countersunk enlargements k' at the ends of the slots adapted to receive the heads k^2 of clamp bolts k^4 . Each clamp nut is tapped into its respective eccentric and when set "home" its head k^2 will fit into its respective countersink or socket, and afford means for firmly clamping the eccentric to the disk. The eccentrics K are loose upon the shaft J, while the disks K' are keyed fast to the shaft.

The ends of the slots k correspond to the positions which the eccentrics require to be placed to reverse the engines, so that when the clamp bolts are released and reset at the other end of slots, the eccentrics will be thereby reversed in position and the engines correspondingly reversed. The slots k provide for the reversing movements being accomplished without removing the clamp bolts entirely from the eccentrics, as it is only necessary to turn them backward far enough

to remove the heads k^2 beyond the outer faces of the disks K' when the eccentrics can be turned to their reversed position by sliding the clamp bolts around in the slots until the head k^2 comes opposite the other socket k^4 . After being released the eccentrics can be reversed, in turn reversing the valve. In this way provision is made for reversing the cutter wheel, without requiring any movement of the machine as a whole, and independently of the gearing. Such reversal of the cutter wheel becomes necessary frequently when the cutters are stalled or the wheel becomes choked or clogged. The reversal causes the clearance of the kerf, removes cuttings, and frees the wheel, so that it is made ready to again advance and remove the coal in front of it.

It will be seen that I have arranged the driving gearing L, H in such way that the power can be economically applied to its utmost and without lateral strain on the shaft. And it will be particularly noted that this gearing is in the vertical longitudinal planes of the wheels N N which support and guide the bed upon the rail N'. But a single rail is used upon which a species of balance is maintained as between the parts at the inner side of the machine and the parts at the outer side. The rapid and powerful reciprocations of the engine casings interfere with this balance and cause vibrations and lateral motion to the machine which seriously interfere with its proper operation, but by arranging the gearing and the engines in the way described relatively to the supporting wheels and the single track rail I largely overcome these disturbing tendencies.

The cutter wheel and wheel carrier are adjusted around the axis of the wheel driving shaft G by means of the arm O and its actuating devices. This arm is rigidly bolted at o to the cutter wheel support. It extends forward longitudinally, and along the inner side, of the machine. At its outer end it is connected with the adjusting plate O', the latter having ears o' , one above and one below the end of the arm, and a spring or springs o^2 being interposed between the arm and the ears. To hold the parts properly together a pivot bolt o^3 is passed through the ears o' , the arm and the springs. These springs serve to provide a yielding connection between the arm O and its adjusting devices so that the adjustment of the wheel carrier about its horizontal axis is yieldingly controlled. This is of great importance where it is desired to adjust the cutter wheel in vertical planes while it is in working position in a vein of coal, the yielding nature of the control of said adjustment insuring that none of the operative parts of the mechanism will be unduly strained.

The plate O' is moved up, or down by means of the pinion O' on the end of shaft O' 130

which is mounted in a standard O^5 carried by the bed A . O^5 is a worm wheel on the end of the shaft O^3 , and with it engages a worm P on the end of a shaft p which extends to the front end of the machine and is provided with a hand wheel P' .

After the wheel support is released at e^5 , the operator can adjust it in one direction or the other around its axis by turning the hand wheel P' in the proper direction which through the trains of devices just described elevates or depresses the arm O .

The machine is automatically advanced bodily along the face of the coal by means of the carriage moving shaft Q mounted in standards on the bed frame. This shaft has a rope drum Q' . The rope Q^2 is secured to the drum and wound upon it, one end being secured to a stationary point suitably distant, as for instance to a post secured in the mine. The drum Q' is rotated by means of the gear wheels R, R' , the wheel R' being on a countershaft R^2 which receives motion through a ratchet driving mechanism comprising the ratchet wheel S , the radius arm S' and the arm S^2 carrying the ratchet dog S^3 . In the present machine these parts are so arranged that they can be actuated directly from the wheel driving-shaft G by means of the rectilinearly reciprocating rod T . This arm is at one end connected directly to the downwardly extended radius arm S' . At the other end it is connected to the eccentric strap T' . The eccentric U is formed with a slot u which fits a squared portion u' of a sleeve U' keyed to the shaft G so that it can be adjusted to have more or less eccentricity. It is rigidly clamped in position by means of the hand wheel nut V which engages with the threaded extremity of the shaft see Fig. 4. The eccentric strap is formed with a handle t . The operator can at any time regulate the feed of the machine by loosening the hand nut V and moving the eccentric so as to be more or less concentric with the shaft, by means of the handle t . After such adjustment the eccentric is firmly fastened in place by the clamping devices.

50 The part e of the cutting wheel is formed with the entire circle e' of the hub of the wheel, the interior of the hub being provided with an annular bushing e^1 secured in place movably by set screws e^2 as shown in Fig. 20. In this figure the part e' is shown entirely detached from the part e to illustrate its construction more fully.

55 The adjacent edges of the two parts of the cutting wheel are formed with flanges e^6, e^7 , the flange e^6 having a groove and the flange e^7 having a corresponding rib to assist in holding them together when secured by the bolts e^8 .

The cutting wheel is provided with an

annular rib C^2 on its upper surface, with the inner edge overhanging, to afford means for the insertion of a curved clamp plate C^3 on the hanger plate D , whereby the cutting wheel is additionally supported while being operated.

70 The plates D and D' are united at the center of the cutting wheel by a stub shaft D^2 , the stub shaft being secured to the plates D and D' by screws D^3 passing through both the plates D and D' and the stub shaft D^2 , as shown in Fig. 4. The stub shaft fits into the bushing e^4 , the whole thereby forming a journal around which the cutting wheel revolves, and by which it is firmly supported in position horizontally. The stub shaft is provided with a central cavity D^6 connected to the exterior against the bushing by a vent D^7 , and provided with a cap screw D^8 through which oil may be poured into the cavity and be fed by the vent outward to lubricate the bushing.

75 I do not herein claim the idea of providing means supplemental to the adjusting arm O and supplemental to its adjusting devices for fastening a wheel support in either of several positions, nor the broad idea of interposing in the train of devices for adjusting the wheel support, a spring adapted to yieldingly control the adjustment of said support; claims for these subjects-matter being presented in my application No. 660,267, filed Nov. 30, 1897.

80 What I claim is:

1. The combination with a main frame or bed, of means for supporting and guiding the bed along the ground, a laterally projecting cutter wheel, an adjustable support for said wheel, an arm connected to said support for adjusting it and the wheel, a bodily adjustable gear plate adapted to impart motion to the arm in opposite directions, springs interposed between the gear plate and the arm, and means for adjusting and locking the gear plate.

85 2. In a mining machine, the combination with a main frame or bed, of means for supporting and guiding the bed along the ground, a laterally projecting cutter wheel, an adjustable wheel carrier for the said wheel, a swingable arm rigidly connected to said wheel carrier, a train of power transmitting devices for actuating said arm in either direction about the axis of the said cutter wheel carrier and having in said train an adjustable gear plate, and oppositely acting springs interposed between said gear plate and said arm.

90 3. The combination with a main frame or bed, of means for supporting and guiding the bed, a laterally projecting cutter wheel, an adjustable support for the cutter wheel, an arm rigidly secured to the wheel support, an adjustable gear plate yieldingly connected

to the said arm on opposite sides thereof, and gearing engaging with the said plate for adjusting the arm.

4. The combination with a main frame or bed, of means for supporting and guiding the bed along the ground, a laterally projecting cutter wheel, an adjustable rocking support for said wheel, an arm connected to said support for adjusting it, a gear plate yieldingly connected to the opposite end of the arm, springs arranged on opposite sides of said arm and interposed between it and said gear plate, and means for adjusting the gear plate.
5. In a mining machine, the combination of a laterally projecting horizontally disposed cutter wheel, a motor, gearing connecting the motor with the cutting apparatus, feeding mechanism for advancing the machine along the face of the coal, and a bed frame constructed substantially as described and supporting all of the aforesaid parts, said bed frame being laterally recessed at points adjacent to the cutter wheel and formed with a laterally projecting sleeve B at the said

recessed or narrowed part having a vertical flange C for supporting the cutter wheel in its working position.

6. In a mining machine, the combination of a laterally projecting horizontally disposed cutter wheel, an adjustable wheel carrier therefor, a motor, shafting and gearing connecting the said motor with the said cutter wheel, feeding mechanism for advancing the machine along the face of the material to be cut, and a bed frame constructed substantially as described and supporting all of the aforesaid parts, said bed frame being laterally recessed or narrowed at points adjacent to the cutter wheel, and formed with a laterally projecting sleeve B having a vertical flange C to which the said cutter wheel carrier is adjustably secured.

In testimony whereof I affix my signature in presence of two witnesses.

EDWIN R. MERRILL.
